US00D874897S

(12) **United States Design Patent** (10) **Patent No.:** **US D874,897 S**
(45) **Date of Patent:** **** Feb. 11, 2020**

(54) **STRAPPING DEVICE**

- (71) Applicant: **Signode Industrial Group LLC**,
Glenview, IL (US)
- (72) Inventor: **Samuel Hochstrasser**, Fällanden (CH)
- (73) Assignee: **Signode Industrial Group LLC**,
Glenview, IL (US)
- (**) Term: **15 Years**
- (21) Appl. No.: **29/705,106**
- (22) Filed: **Sep. 10, 2019**

Related U.S. Application Data

- (63) Continuation of application No. 29/598,733, filed on
Mar. 28, 2017.

(57) **CLAIM**

The ornamental design for a strapping device, as shown and
described.

DESCRIPTION

FIG. 1 is a front top right-side perspective view of a
strapping device of one embodiment of our new design.

FIG. 2 is a front elevational view of the strapping device of
FIG. 1.

FIG. 3 is a rear elevational view of the strapping device of
FIG. 1.

FIG. 4 is a right-side elevational view of the strapping
device of FIG. 1.

FIG. 5 is a left-side elevational view of the strapping device
of FIG. 1.

FIG. 6 is a top plan view of the strapping device of FIG. 1.

FIG. 7 is a bottom plan view of the strapping device of FIG.

1; and,

FIG. 8 is a rear bottom left-side perspective view of the
strapping device of FIG. 1.

The broken lines in the drawings depict portions of the
strapping device which form no part of the claimed design.

1 Claim, 8 Drawing Sheets
